UNITED STATES PATENT OFFICE

2,461,457

DRAPEY CRANE

Henry Weber, Cleveland, Ohio, assignor of one-fourth to Harry A. Hildebrand, Brunswick, Ohio

Application April 16, 1947, Serial No. 741,871

5 Claims. (Cl. 211—105.1)

1

The invention relates to drapery cranes and particularly to devices of this character that are universally adjustable whereby they can be mounted on the supporting framework, such as a window or door frame, either at the top thereof or on a side member either with a vertical or a horizontal positioning of the supporting bracket, or at any desired angle, or so as to support the drapery at the desired height or at any desired distance of lateral offset relative to the window or door frame, or inwardly of the latter at the desired spaced distance therefrom. By such adjustment, the drapery can be supported by the crane with the latter adjusted relative to the frame so as to extend across the top thereof, or at the side thereof, in any desired angular position, or above the frame at a desired height, or inwardly of the frame the desired distance to accommodate other window covers, such as shades, valances, glass curtains, etc., between the drapery and the window proper. The crane also can be adjusted so as to correct any irregularity in the hanging of the drapery or improper hanging thereof relative to the window or the room floor due to improper installation, sagging, or shrinkage. This universal adjustment permits the necessary accommodation to obtain the desired ornamental effect, also to conform to the particular window frame involved, and to correct draping irregularities resulting from faulty installation, use, or laundering.

Particularly, the improved drapery crane is of the cantilever type, the drapery carrier being pivotally secured at one end to a crane bracket adjustably mounted on the window or door frame.

The annexed drawings and the following description set forth in detail certain means illustrating the improvements in drapery cranes, the same, however, disclosing only one form in which the principle of the invention may be embodied.

In said annexed drawings:

Figure 1 is a front elevation of the improved drapery crane, the parts of which are shown in full lines secured and adjusted for a mounting of the supporting bracket at the top of and within a lateral edge of a window frame in horizontal parallel relation to the cantilever arm forming a carrier for the drape, the cantilever arm being shown broken, and two selective angular positions, in a vertical plane, of the cantilever arm being suggested by dot-and-dash lines;

2

Figure 2 is a bottom plan view in full lines of the crane as shown in Figure 1, partially in horizontal section, and upon a smaller scale, an adjustable position of the cantilever arm in a horizontal plane being suggested in dot-and-dash outline;

Figure 3 is a vertical section, taken in the plane indicated by the line 3—3, Figure 2;

Figure 4 is a fragmentary vertical section, taken in the plane indicated by the line 4—4, Figure 3;

Figure 5 is a fragmentary plan view, taken from the plane indicated by the line 5—5, Figure 3;

Figure 6 is a front elevation illustrating an angular mounting of the supporting bracket adjacent an upper corner of the window frame and a supporting of the cantilever arm at a selective distance above and exteriorly offset from the side edge of the window frame;

Figure 7 is a front elevation showing the supporting bracket and cantilever arm positioned in horizontal parallel relation, the supported end of the cantilever arm being offset exteriorly of the window frame to a selective extent; and

Figure 8 is a front elevation showing the supporting bracket mounted in vertical position and carrying the cantilever arm in horizontal position at a selective distance above the main supporting frame.

Referring to the annexed drawings in which the same numbers indicate the same several elements in the respective views, the improved crane has a supporting bracket 1 having a relatively right-angular extension 11, Figures 1 and 2, the bracket portion 1 being capable of adjustable support in any desired position on the window frame 4 by means of a pair of spaced elongated slots 2 formed in the body 1, and cooperating adjusting screws 3. Various illustrative adjustable positionings of the bracket 1 on the window frame 4 are illustrated in the accompanying drawings, Figures 1 and 2 showing the supporting of the bracket 1 on the window frame 4 at the top of the latter and in a horizontal position of the body 1, Figure 6 illustrating the supporting of the body 1 adjacent an upper corner of the window frame 4 at about a 45° angle and extending above the window frame 4 in an outwardly offset relation, Figure 7 illustrating a further horizontal mounting of the body 1 on the window frame 4 but in such position that the end of the body 1 extends

outwardly a desired offset distance beyond the edge of the window frame 4, and Figure 8 illustrates a mounting of the body 1 vertically of the window frame 4 and adjacent an edge thereof and extending above the window frame. All of these mountings are adjustable in a direction longitudinally of the respective positions of the body 1 by means of the elongated slots 2 and the screws 3.

Adjustably secured to the angular extension 11 of the drapery bracket 1 is a cylindrical rod 10. This adjustable mounting of the rod 10 is effected as follows. Welded, as indicated by "6," Figure 4, to the outer face of the angular extension 11 is one edge of an elongated spring plate 5, of channel formation in cross-section, Figure 4, whose opposite edge 8 is secured to the angular extension 11 a spaced distance from the inside face of the angular extension 11 by screws 9. An intermediate portion 7 of the spring plate 5 is of inner concave formation forming an inner journal surface in which is rotatably mounted the rod 10, the latter having also a line bearing on the inside face of the bracket extension 11. The rod 10 extends outwardly beyond the free end of the angular extension 11. It is evident that a loosening of the screws 9 will permit the turning of the rod 10 in the journal portion 7 of the spring plate 5 and also its adjustment longitudinally of the spring plate 5. Such turning of the rod 10 permits the positioning of a cantilever type drapery carrier 11-12 secured at one end to the top of the rod 10 in any desired angular position relative to the bracket 1 in a plane parallel to the bracket 1. Several such positions are shown in the accompanying drawings. The longitudinal adjustment of the rod 10 extends this angular adjustment to a plurality of parallel planes so that the distance of the drapery carrier 11-12 from the bracket 1 can be adjusted as desired. Furthermore, the drapery carrier 11-12 is pivotally secured to the top of the rod 10.

The drapery carrier comprises two tubular telescoping parts 11 and 12 whereby the effective length of this cantilever carrier may be selected, according to the width of the window and the particular mounting desired, the telescoping action and the secure holding together of the two parts 11 and 12 being permitted and effected by inwardly extended spring beads 13 formed in the outer cantilever member 12 and adapted to engage grooves 14 formed in the exterior surface of the inner telescoping cantilever member 11. The inner pivotally connected end of the drapery carrier 11-12 is squeezed into compact condition and the beads 13 and grooves 14 are provided in multiple and in longitudinal spaced relation in this end of the carrier 11-12.

Fixed in the free end of the rod 10 is a pin 15, Figures 1 and 2, which provides at its ends journal surfaces for cylindrical enlarged leg portions 17 of a two-leaf yoke member whose superposed plates 16 are secured in the inner end portion of the cantilever member 12.

The various mountings obtainable by the several adjustments will be readily apparent.

The plane of turning movement on the axis of the pin 15 is at right angles to the plane of turning movement of the rod 10. Adjustment of the drapery carrier 11-12 in a vertical plane by the turning of the rod 10 is suggested in Figure 1, and adjustment in a horizontal plane by a pivotal movement on the pin 15 is suggested in Figure 2.

As hereinbefore stated, Figure 6 illustrates the carrying of the drapery above and outwardly off-

set from the window frame, Figure 7 illustrates a horizontal carrying of the drapery outwardly offset from and at the height of the window frame, and Figure 8 illustrates a carrying of the drapery well above the window frame but not offset therefrom. The desired extent of any of these various positions can be selected by means of the elongated slots 2 and adjusting screws 3.

What I claim is:

1. A drapery crane comprising a bracket having a relatively right-angular end extension, a resilient member of channel cross-section welded adjacent one edge to the end extension and having an inner concave portion forming a bearing intermediate its edges, a rod rotatably mounted at one end in the bearing and having an opposed bearing on a face of the end extension, means for releasably securing the rod in the channel and to permit the turning of the rod to a selective rotative position, a pin mounted in the other end of the rod, and a cantilever drapery carrier pivotally mounted at one end on the pin to turn in a plane at right angles to the plane of rotative movement of the rod.

2. A drapery crane comprising a bracket having a relatively right-angular end extension, a resilient member of channel cross-section welded adjacent one edge to the end extension and having an inner concave portion forming a bearing intermediate its edges, a rod rotatably mounted at one end in the bearing and having an opposed bearing on a face of the end extension, means for releasably securing the rod in the channel and to permit the turning of the rod to a selective rotative position, a pin mounted in the other end of the rod, and a cantilever drapery carrier having an end yoke formation pivotally mounted on the pin ends to permit a pivotal movement of the carrier in a plane at right angles to the plane of rotative movement of the rod.

3. A drapery crane comprising a bracket formed with spaced longitudinally-extended elongated slots and having a relatively right-angular end extension, a resilient member of channel cross-section welded adjacent one edge to the end extension and having an inner concave portion forming a bearing intermediate its edges, a rod rotatably mounted at one end in the bearing and having an opposed bearing on a face of the end extension, means for releasably securing the opposite edge of the resilient member to the end extension to retain the rod and to permit the turning of the latter to a selective rotative position, a pin mounted in the other end of the rod, and a cantilever drapery carrier pivotally mounted at one end on the pin to turn in a plane at right angles to the plane of rotative movement of the rod, the carrier having relatively telescoping portions.

4. A drapery crane comprising an elongated bracket having a relatively right-angular end extension, means for adjustably supporting the bracket longitudinally of its length, a cylindrical rod having a bearing on the bracket extension and projected beyond said extension, a resilient plate formed with an opposed rod-bearing portion, means for releasably clamping the plate in constricted position for rotative movement of the rod on its bearings and adjustment thereof axially of its bearings, and a cantilever drapery carrier pivotally mounted on the projected part of the rod to turn in a plane at right angles to the plane of rotative movement of the rod.

5. A drapery crane comprising an elongated bracket having a relatively right-angular end ex-

tension, means for adjustably supporting the bracket longitudinally of its length, a cylindrical rod having a bearing at one end on the bracket extension and projected at its opposite end beyond said extension, a resilient plate secured to the bracket extension and formed with an opposed rod bearing, means for releasably clamping the resilient plate to the bracket extension for rotative movement of the rod on its bearings and adjustment thereof axially of its bearings, a pin 10 mounted in the projected portion of the rod, and a cantilever drapery carrier pivotally mounted at one end on the pin to turn in a plane at right angles to the plane of rotative movement of the rod.
